UNITED STATES PATENT OFFICE.

VINCEN P. McVOY, OF MOBILE, ALABAMA, ASSIGNOR TO PHOENIX MACHINE WORKS,
OF MOBILE, ALABAMA.

AUTOMATIC PUMP AND BOILER FEEDER.

Application filed April 7, 1923. Serial No. 630,659.

To all whom it may concern:

Be it known that I, VINCEN P. McVoy, a citizen of the United States, residing at Mobile, in the county of Mobile and State of Alabama, have invented certain new and useful Improvements in Automatic Pump and Boiler Feeders, of which the following is a specification.

This invention relates to pumps, and more particularly to that class of devices designed as a boiler feeder, and it has for its object primarily to provide a simple and efficient and reliable device for dry kilns, steam heated plants, or for any other use or place where it is desired to put the water of condensation back into the boiler without the loss of temperature.

It has for a further object to provide a device for this purpose which shall serve the purpose of the ordinary steam trap, thus allowing of the dispensing of such trap, as it serves not only the same function as an ordinary steam trap but goes further and not only separates the water from the steam but returns the water to the boiler without materially reducing its temperature.

There are not any packing glands, stuffing boxes, screw stems, piston rods or any other parts exposed or partly exposed; all the mechanism is enclosed and requires absolutely no lubrication, as it is constructed of suitable anti-friction metals so as to eliminate the necessity of lubrication. It also eliminates the stopping up of the kiln with cold water due to steam traps not working properly. It will increase the temperature of the kiln from 25% to 30% and sometimes even more. It will prolong the life of the boiler due to the feeding of the hot water instead of cold, reduces the consumption of fuel and increases the boiler power, yet will give practically no trouble or require attention to keep it in working condition. The returned water of condensation serves to supply the boiler. It will eliminate the biggest portion of mud and other impurities that are deposited in the boiler from the use of bad water, and it also acts as an insurance against low water at night, as well as day.

It is capable of application to any boiler in a short time and without the employment of skilled labor. The engineer can readily see the working of the device; when the water rises in the glass the ma-

chine is filled with the water of condensation from the kiln and when the water is going down in the glass it is discharging its contents into the boiler.

Other objects and advantages of the invention will hereinafter appear and the novel features thereof will be specifically defined by the appended claims.

The invention, in its preferred form, is clearly illustrated in the accompanying drawings, which, with the numerals of reference marked thereon, form a part of this specification, and in which—

Figure 1 is a substantially central vertical section with parts broken away.

Figure 2 is a side elevation with portions broken away and parts in section.

Figure 3 is a top plan with the base broken away.

Figure 4 is a vertical longitudinal section on the line 4—4 of Figure 3.

Figure 5 is a vertical section on the line 5—5 of Figure 2.

Figure 6 is a detail perspective view of the weight-operating arm.

Figure 7 is a section taken on the line 7—7 of Figure 2.

Figure 8 is a vertical transverse section on the line 8—8 of Figure 3.

Like numerals of reference indicate like parts throughout the several views.

Referring first to Figure 1, the cylinder is shown at 1, and the base on which it rests at 2. The base is provided with suitable means, as the lugs 3 to receive the screws or bolts or other means employed to secure the cylinder in position. In the present instance the lower end of the cylinder 1 is provided with the inwardly-extended flange 4, and the base with the outwardly extended flange 5 on which the flange 4 rests as seen in Figure 1, the base and cylinder being secured together by suitable means as the bolts 6 passed through the said flanges 4 and 5.

The base 2 is provided with the discharge pipe 7 having a check valve 8 therein as seen in Figure 1 whereby the water of condensation from the cylinder 1 is conveyed to the boiler or boilers, not shown.

At its upper end the cylinder 1 has a broad horizontal extension as seen at 9 provided with holes 10 for the reception of bolts or the like 11 which serve to secure in place thereon the hood or cover 12 which

serves to protect the working parts which are mounted on the extension 9 as will be readily understood from Figure 1.

At the upper end of the cylinder there is provided an inlet pipe 13 with check valve 14 for the inlet of the water of condensation from the dry kiln, radiators or other source.

15 is a float within the cylinder 1 as seen in Figure 1, of which 16 is the stem, the lower end of which is pivotally connected as at 17 with the free end of the curved arm 18, which is pivotally mounted as at 19 on the supporting member 20 mounted in the wall of the cylinder as shown in Figure 1. The float is free to slide up and down on its stem, the upper end of which latter is pivotally connected as at 21 with the end of the lever 22 which is pivotally mounted as at 23, the pivot being mounted in the bearings 24, 25 and 26 rising from the plate 28 which is secured on the top of the plate or extension 9 by suitable means, as the screws or the like 27, as seen in Figures 3 and 7.

The lever 22 is loosely mounted on its pivot 23 and around the latter is a bushing 29 which prevents binding of the parts mounted thereon so that the lever 22, the counterbalance weight and the weight proper all move with ease and all liability of sticking is prevented.

The lever 22 as seen in Figure 6 has the end farthest from its pivot end a lateral extension 30 with ears 31 and 32 with openings for the reception of the said bushing, and each of these ears is provided with the cut away portion 33 providing the pairs of shoulders 34 and 35 as seen best in Figure 6, for a purpose that will soon be made clear. The ears 31 and 32 are disposed between the bearings 25 and 26 as seen in Figure 7.

36 is a weight having the ears 37 and 38 which are disposed upon the bushing 29 between the ears 31 and 32 of the lever 22, as seen best in Figure 7, the said weight being arcuate in form as seen in Figures 1 and 4 having in one acting face a plug 39 and in 50 the other acting face a spring bumper or cushion 40 retained therein in any suitable manner. The weight 36 is formed with the lugs 41 and 42 one upon either side as seen best in Figure 3, for a purpose which will be later described.

43 is a counterbalance provided with a lug 44 which is mounted to turn on the bushing 29 as seen best in Figure 7. The lever 22, the weight 36 and the counterbalance 43 are all movable on the bushing independently of each other for a part of their movement, but in other parts of their movements all three move together, and again only two of them move together; this will be made clear as the description proceeds,

and the object thereof clearly stated. This weight or counterbalance aids in the movement of the weight 36 till the latter passes the vertical centre when the counterbalance 43 has moved to its lowermost limit, the weight 36 then needing no assistance, as it falls by gravity.

Mounted on the pivot 23 is the rocker arm 45 having a cut away portion 46 and the shoulders 47 and 48 at opposite ends of the said cut away portion as seen best in Figure 4, the lug 42 being adapted to cooperate with the shoulder 48 as seen in the said Figure 4. This rocker arm has the extended sleeve 49 to embrace the pivot 23, see Figures 4, 5 and 7, and serves to maintain the parts in proper position.

Pivotally mounted on the side of the rocker arm 45 as seen at 50 is the member 51 adapted to slide endwise on the plate 28 as seen in Figures 2 and 4, and this member 51 has in its upper face a notch or the like 52, see Figures 2 and 4, for a purpose as will soon be seen. The forward end of this member 51 is preferably tapered or rounded as seen at 53 and is adapted to engage and move on its pivot a gravitating member 54, pivoted at 55 on the member 56 pivoted at 57 on opposite sides of the steam inlet pipe 58 secured in and rising from the member 9 as seen clearly in Figure 4 and having a lateral branch 59. The free end of the member 56 has mounted on one side thereof a roller 60 which is adapted for cooperation with the notch 52 in the member 51 as seen in Figure 4. When the member 51 is moved to the right in Figure 2 the roller 60 is moved out of the notch 52 and rides upon the upper face of the said member 51, being shown in such latter position in Figure 2, and in the notch in Figure 4. The upper face of the member 56 is provided with an opening 61 through which works the cam or projection 62 on the gravitating member 54, while the top portion 63 of the said member 56 is adapted to engage the under face of the projecting end of the valve stem 64 of the pilot valve 65 as seen in Figure 2. The upper face of the member 54 has a shoulder 66 which is adapted to engage the stop member 67 on the top of the member 56 to limit the movement of the said member 54 upward as seen in Figure 4.

The valve 65 and its stem work in the chamber 68, the stem being provided with the longitudinal passages or channels 69 as seen in Figure 4 and the valve being fitted to a seat 70 in the valve chamber 71 from which leads the passage 72 near the top to the space above the steam valve piston 73 in the lateral branch 59 of the steam inlet pipe 58 as seen in Figure 4. 74 is an exhaust passage from the chamber in which works the valve stem 64.

75 is a tubular member held in the ex-

tension 9 and with its lower end open to the atmosphere, as seen in Figures 1, 2, 4 and 8. This tubular member is provided with a valve seat 76 for a valve 77 provided with the longitudinal grooves 78, all as seen clearly in Figure 8. This valve is provided with a slot or recess 79 in which is received the lateral projection 80 on the member 81 pivoted at 82 on the member 83 which is rigid with the tubular member 75. The free end of the member 81 is extended at substantially a right angle, in this instance being shown as curved to form the arm 84 which extends across the member 51 as seen in Figures 2, 3 and 7 and the under face of this portion or arm 84 is tapered as seen at 85 in Figures 2 and 4 to engage in the notch 52 of the slidable member 51 at predetermined times. It is shown as engaged 20 in said notch in Figure 2, the roller 60 having moved out of the said notch.

86 is a stop for the weight 36 when the latter is in the one position, that seen in Figure 4. It may be secured in any suitable manner, in the present instance having one end seated in a recess 87 in the under side of the plate 28 and its other end secured between the top of the cylinder and the cover 42 by one of the bolts 11 as seen in Figures 1, 2 and 4.

Integral with the lateral branch 59 of the steam inlet pipe 58 is the chamber 88 in the lower portion of which is a valve seat 89 for a valve 90, see Figure 8, the bottom of the valve chamber being open to the interior of the machine beneath the cover 12. The valve 90 has the depending lug or the like 91 as seen in Figures 1, 2, 4 and 8 to be engaged by the projection 62 on the gravitating member 54 as seen in Figure 2 where the said projection is engaged with the said lug 91 and has raised the valve 90 from its seat.

The upper portion of the valve 90 is provided with a bleed or equalizing hole affording communication between the space above the said valve and the lateral branch 59 of the steam inlet pipe 58 as seen in Figures 2, 4 and 8, this bleed 92 affording communication between the space above the steam inlet valve 90 and the chamber 88, as will be best understood from Figures 2, 4 and 8.

The valve chamber 88 is provided with a removable closure 93 and the top of the chamber 68 is provided with a removable closure 94, as seen in Figures 2, 3 and 4 for an obvious purpose.

In use, the inlet pipe 13 is connected up with the dry kilns or the radiators of a heating plant, or other source of water of condensation, the discharge pipe 7 is connected up with the boiler to convey the water of condensation thereto, and the pipe 95 is connected with the steam space of the

boiler. The device herein described and shown is suitably supported at a point above the water line of the boiler. Thus connected up the operation is as follows:—

With the float down and the cylinder 70 empty the parts are in the position shown in Figures 1 and 4; they remain in this position till the float has risen so that it strikes the stop 96 on the float stem, and then the further upward movement of the float will move the arm 22 on its pivot, carrying with it the weight 36 by reason of the engagement of the shoulders 35 with the lugs 41 and 42 of the weight 36 as shown in Figures 3 and 4. Then the further movement of the float will move the arm 22 to such a point that the weight 36 will be thrown or brought up gradually till its center of gravity passes the vertical when it falls of its own weight and rests upon the counter balance 43. When the weight is in the position in which it is shown in Figure 4 the lug 42 is resting against the shoulder 48 of the rocker arm 45 as seen in Figure 4, the weight not being supported by the arm or lever 22. As the float rises and moves the arm 22 the shoulders 35 of the said arm are brought into contact with the lugs 41 and 42 of the weight and continued movement brings the weight into its vertical position, but in the meantime the counter balance 43 has struck the extension 9 and comes to rest. When the weight 36 passes the centre it falls upon the counter balance and is there supported, the spring buffer 90 cushioning the stroke. It will be understood that the inflow of the water of condensation from the radiators or other source gradually causes the float, the same being guided upon its stem, to rise. After the weight 36 passes the centre it falls for a short distance and then the lug 42 coming in contact with the shoulder 47 of the rocker arm 45 and moving the rocker arm on its pivot forces the member 51 to the right in Figure 4 and the roller 60 is forced upward out of its notch 52 and the roller then rides upon the upper edge of the said member 51 into the position seen in Figure 2. This forces the portion 63 of the member 56 upward till it contacts with the stem of the pilot valve 65, forcing the same upward and unseating the said valve, allowing the exhaust

of the pressure above the steam valve 90 to pass through the passage 72 and down the grooves 69 of the stem and out through the passage 74 to the interior of the pump, as will be readily understood from Figures 2 and 4. This actuation of the valve 65 occurs just before the steam valve 90 is unseated so as to relieve the pressure from above the same so that the steam valve may be readily unseated by the steam pressure from the boiler acting upon the under side of the piston portion 73 of the steam inlet valve 90. The

95

100

105

115

120

125

130

member 51 having been moved so that its end 53 is out of contact with the gravitating member 54 the latter falls into the position shown in Figure 2 and the portion 62 thereof comes under the lug 91 of the valve and the valve is thus held in its open or raised position. The steam from the boiler, entering through the pipe 95 flows into the cylinder on top of the water that has accumulated 10 therein forcing the same out through the outlet 7 to the boiler, the float gradually falling with the water. The gravitating member 54 serves to retain the steam valve in open position notwithstanding equalization of the pressure upon both sides of the valve, after the first rush of steam to unseat the valve.

As the float falls it moves the arm or lever 22 downward a short distance before it picks 20 up the weight, by reason of the space between the shoulders 34 and 35 being much greater than the thickness of the lugs 41 and 42 on the opposite sides of the weight 36. When the inrushing steam raises the steam 25 valve 90 from its seat the valve 14 is automatically closed and the inflow of the water of condensation stops. This valve 14 remains closed till the cylinder is empty. When the steam enters and lifts the steam 30 valve 90 the pressure on top of the water in the cylinder 1 forces open the valve 8 and the water flows to the boiler, until the cylinder 1 is emptied, or practically so, that is, till the float has reached its lowermost 35 position.

After the float has fallen a prescribed distance it picks up the weight, that is the shoulders 34 engage the lugs 41 and 42 on the weight and brings the weight to its vertical position, the float then being practically at the bottom of the cylinder as seen in Figure 1. When the float moves just a fraction more the weight falls by its own weight and strikes the member 86 as seen 40 in Figure 4. When the weight falls the member 51 is moved so as to assume the position shown in Figure 4, the roller 60 falling into its notch 52 and at the same time the rounded end 53 of the member 51 engages the adjacent portion of the gravitating member 54 and knocks it out from under the lug 91 on the valve and the latter falls to its seated position, thus shutting off the steam. It is to be understood that the valve 45 55 is also seated as the parts are returned to their normal position. During the movement the arm 84 riding upon the member 51 is forced out of its notch and up on top of the member 51 as seen in Figure 4; this 60 raises the valve 77 from its seat, allowing the escape of any air that may be accumulated in the radiators or dry kilns. The steam remaining in the cylinder 1 will condense till it is at a point less than that in 65 the radiators or kilns.

By means of the mechanism just described I am enabled to open a valve of greater area than otherwise could be done, and which is necessary in order to obtain rapid movement and emptying of the cylinder, 70 being limited to space and weight. It is to be noted that counter balance counterbalances the lever 22, the arm 18, the float stem 16, and parts carried thereby, and at the same time upon the return movement 75 of the weight it does not add to the original weight as the original weight is picked up at an angle of substantially 45° and then the counterbalance is picked up but adds no extra weight. The arm 22 and the weight 80 36 are moved together to a point of ease before picking up the counter balance, and at that point the two move as easily as did the weight 36 at the start. The arm 22, the weight 36 and the counterbalance are all 85 loosely mounted on the bushing, and have movement independently of each other. It is to be noted that the members of the pick-up device are all loosely mounted on the shaft so as to insure ease of movement. 90

Modifications in detail, proportion of parts, etc., may be resorted to without departing from the spirit of the invention or sacrificing any of its advantages.

What is claimed as new is:—

1. An automatic pump or boiler feeder comprising a float controlled by inflow of water of condensation, a steam inlet valve, means embodying a pick-up device a weight and a counter-balance, both the weight and the counterbalance being positively controlled by the float for controlling said valve said weight movable past the vertical central line to bodily contact with said counter-balance. 100

2. An automatic pump or boiler feeder comprising a float controlled by water of condensation, a steam inlet valve, means embodying a pick-up device, a weight and a counter-balance, both the weight and the counter-balance being positively controlled by the float for controlling said valve said weight movable past the vertical centre line to bodily contact with said counter-balance, and an air exhaust valve positively controlled by the pick-up device. 105

3. An automatic pump or boiler feeder comprising a steam inlet valve, a float controlled by the inflow of water of condensation, and an oscillatory member controlled 110 by the float for opening said valve, and an oscillatory aid to said member movable therewith for a portion only of the travel of the said member, said member and aid adapted to bodily contact with each other at 115 an extreme of the movement of the float.

4. An automatic pump or boiler feeder comprising a steam inlet valve, a float controlled by the inflow of water of condensation, means including a pick-up device, a 120

95

105

115

120

125

130

weight and a counter-balance, both the weight and counter-balance being interposed between the float and valve for opening the latter, said weight movable past the 5 vertical centre line to bodily contact with said counter-balance and means including an air exhaust valve positively controlled by said pick-up device.

5. An automatic pump or boiler feeder 10 comprising a cylinder, a float therein controlled by the inflow of water of condensation, a steam inlet valve, an oscillatory weighted member actuated by the float, and an oscillatory aid to said member movable 15 therewith for a portion only of the travel of the said member, said weighted member and aid being mounted on a common pivot and the weighted member movable into bodily contact with said aid at one extreme 20 of the movement of the weighted member, and means interposed between the weighted member and valve for unseating the valve by the movement of the weighted member.

6. An automatic pump or boiler feeder 25 comprising a cylinder, a float therein controlled by the inflow of water of condensation, a steam inlet valve, an oscillatory weight actuated by the float, a counter balance on the pivot of said weight, and a pilot valve controlled by said weight for initially exhausting the pressure from the space above the top of 30 said steam inlet valve.

7. In an automatic pump or boiler feeder, 35 a float controlled arm, a counter balance and an oscillatory weight cooperable with said counter balance, said elements movable in unison and also, for a part of their movement, independently of each other an air exhaust valve, and an independently 40 slidable arm actuated by the movement of the float controlled arm for actuating said air exhaust valve.

8. In an automatic pump or boiler feeder, 45 a float controlled arm, a counter balance, an oscillatory weight cooperable with said counter balance and actuated by said arm, an exhaust valve, and an independently 50 slidable arm actuated by the movement of the float-controlled arm for actuating said exhaust valve.

9. In an automatic pump, a float-controlled arm, a counter balance, a weight cooperable with said counter balance, and means for actuating said weight, and an air 55 exhaust valve, and an independently slidable arm actuated by the movement of the float-controlled arm for actuating said air exhaust valve.

10. In an automatic pump or boiler feeder, a float-controlled arm, a counter balance, a weight movable in both directions beyond the vertical central line, and a rocker arm actuated by the movement of the 60 weight, an air exhaust valve, and an in-

dependently slidable arm actuated by the movement of the rocker arm for actuating said air exhaust valve.

11. In an automatic pump or boiler feeder, 70 a float-controlled arm, a steam inlet valve, an oscillatory weight the pivot of which is that of the arm, a pilot valve controlled in its movements by the said float-controlled arm, an air exhaust valve, and an independently slidable arm actuated by 75 the movement of the float-controlled arm for actuating said air exhaust valve.

12. In an automatic pump or boiler feeder, 80 a float-controlled arm, a counter balance, an oscillatory weight, all mounted on the same pivot but movable independently of each other, a steam inlet valve, and a pilot valve controlling means positively controlled by said weight for initially exhausting the pressure from the space above the top of 85 said steam inlet valve.

13. In an automatic pump or boiler feeder, 90 a float-controlled arm, a counter balance, an oscillatory weight all mounted freely on the same pivot for independent movement and for movement together for a portion of their travel, a steam inlet valve and a pilot valve controlling means positively controlled by said weight for initially exhausting 95 the pressure from the space above the top of said steam inlet valve.

14. In an automatic pump or boiler feeder, 100 a float-controlled arm, a counterbalance, an oscillatory weight all mounted freely on the same pivot for independent movement for a portion of their travel and for movement together for another portion of their travel.

15. In an automatic pump or boiler feeder, 105 a float-controlled arm, a counter balance, a weight movable with the counter balance for the initial part of the travel of the counter-balance and afterwards independently thereof, a rocker arm and valve-actuating devices, all controlled by the movement of said float controlled arm said weight and counter balance being mounted on the same pivot.

16. In an automatic pump or boiler feeder, 115 a float-controlled arm, an oscillatory weight, a counter balance and a rocker arm all movable on the same pivot, the weight being movable with the counter balance for the initial part of the movement of the same and afterwards independently thereof, and a slidable member carried by the rocker arm.

17. In an automatic pump or boiler feeder, 120 a float-controlled arm, an oscillatory weight, a counter balance and a rocker arm all movable on the same pivot, a slidable member carried by the rocker arm, and a valve actuating member actuated by the slidable member.

18. In an automatic pump or boiler feed- 125

- er, a float-controlled arm, a steam inlet valve, an oscillatory weight mounted on the pivot of and controlled by said arm, a pilot valve, means actuated by the movement of the said weight to open the pilot valve, and means actuated by the movement of the said means for holding the steam valve open.
19. In an automatic pump or boiler feeder, a steam valve, a pilot valve, and a pivoted member to actuate the pilot valve and subsequently lock the steam valve in open position.
20. In an automatic pump or boiler feeder, a float-controlled arm, a steam valve, a pilot valve, a pivoted member to actuate the pilot valve and subsequently lock the steam valve in open position, and a member to move the locking means from operative position.
21. In an automatic pump or boiler feeder, a steam valve, and a pilot valve arranged for actuation in succession, and a gravitating member to lock the steam valve in open position.
22. In an automatic pump or boiler feeder, a steam valve, a pilot valve, means for opening the pilot valve prior to the opening of the steam valve, a gravitating member to hold the steam valve in open position, and a slidable member to remove said gravitating member from locking position.
23. In an automatic pump or boiler feeder, a steam valve and a pilot valve arranged for actuation in succession, means for unseating the pilot valve prior to the unseating of the steam valve, and a vent controlled by said unseating means said means including an oscillatory float-controlled weighted member.
24. In a device of the character stated, means embodying an oscillatory member movable gravitatingly after passing to either side of the vertical, and a counter balance movable therewith during its initial movement only, said member operating a plurality of valves in succession, and float-controlled means for actuating said means.
25. In a device of the character stated, a steam valve, a pilot valve, a vent valve, means whereby the pilot and vent valves are operated simultaneously, said means including an oscillatory float-controlled weight member and a float-controlled slidable member which effects subsequent actuation of said steam valve by means of said pilot valve.
26. In a device of the character stated, a steam valve, a pilot valve, a vent valve, means whereby the pilot valve and vent valve are actuated simultaneously, said means including a float actuated slidable member which effects subsequent actuation of said steam valve by means of said pilot valve, and a weight and counterbalance for
- said weight movable therewith during the initial movement thereof only.
27. In a device of the character described, a cylinder having an inlet for water of condensation and a separate outlet for such water, and automatic float-actuated means operative by steam pressure, said means embodying an oscillatory weight and a counterbalance therefor, the two being movable together during the initial movement only of the said weight and adapted to bodily contact with each other at one extreme of the movement of the weight.
28. In a device of the character described, a cylinder having an inlet for the water of condensation and a separate outlet for the said water, and float-controlled means for admitting steam, and shutting off the supply of water of condensation, said means embodying cooperating independently movable oscillatory weight and counter-balance, said counter-balance movable with the weight during the initial movement of the weight only, and the two adapted to bodily contact at one extreme of the movement of the weight.
29. In a device of the character described, a cylinder having an inlet for the water of condensation and an outlet therefor, and combined float and weight actuated means for controlling the outlet and inlet and an air-exhaust valve controlled by independently slidable means movable with the weight.
30. In a device of the character stated, a cylinder having an inlet for the water of condensation and an outlet therefor, a normally seated steam inlet valve, and float-controlled means for unseating said valve, said means embodying cooperating independently movable oscillatory weight and counterbalance, and an air-exhaust valve controlled by independently slidable means movable with the float controlled means.
31. In a device of the character stated, a cylinder having an inlet for the water of condensation, and an outlet therefor, a normally seated steam inlet valve, and combined float-controlled and weight means for unseating said valve and an air-exhaust valve controlled by independently slidable means movable with the weight.
32. In a device of the character stated, a cylinder having an inlet for water of condensation and a separate outlet therefor, a float, a normally seated steam inlet valve, an oscillatory weight and independent cooperating means loosely mounted on the same pivot for unseating said valve, and a counter balance for said weight movable therewith during the initial movement only of the latter and adapted to be bodily engaged by the weight in one extreme of the movement of the latter.
33. In a device of the character stated,

a cylinder having an inlet for water of condensation, and an outlet therefor, a normally seated steam inlet valve, and means controlled by the height of water in the cylinder for automatically unseating and seating said valve said means embodying cooperating independently movable oscillatory weight and counter balance said counter balance movable with the weight during the initial movement only of the latter and adapted to bodily contact therewith.

34. In a device of the character stated, means embodying a pick-up device, a weight and an auxiliary aid for said weight said weight and aid being mounted on a common pivot, the weight being movable to bodily contact with the aid in one extreme of the movement of the weight, said means serving to automatically admit water of condensation, control the admission of steam, to positively control the exhaust and hold the steam admission valve open.

35. In a device of the character stated, a steam inlet valve, a pilot valve cooperable therewith, a weight and a float-controlled member carrying a slideable member for actuating the pilot valve and a gravitating member to hold the steam inlet valve open.

36. In a device of the character described,

a steam inlet valve, a pilot valve a slideable member for actuating the pilot valve, and gravitating means controlled by said slideable member for positively holding the steam valve open.

37. In a device of the character described, a steam inlet valve, a pilot valve the latter being operable prior to the unseating of the steam inlet valve, float-controlled means for operating the pilot valve, and a gravitating member to positively hold the steam inlet valve open.

38. In a device of the character stated, a steam inlet valve, a pilot valve, the latter being opened prior to the former a gravitating member adapted to retain the steam valve open after the first rush of steam to unseat the valve, and a vent automatically controlled by the means that controls the pilot valve.

39. In a device of the character stated, a cylinder, a float therein, a pivoted slideable member controlled by the float, a reciprocable pilot valve, a pivoted member, and means carried by said pivoted member for cooperation with said slideable member for unseating the pilot valve.

In testimony whereof I affix my signature.

VINCEN P. McVOY.
